DESIGN FOR A TABLE

Nathan P. Bloom, Louisville, Ky.

Application November 8, 1934, Serial No. 53,929

Term of patent 7 years

To all whom it may concern:

Be it known that I, Nathan P. Bloom, a citizen of the United States, residing at Louisville, in the county of Jefferson and State of Kentucky, have invented a new, original, and ornamental Design for a Table, of which the following is a specification, reference being had to the accompanying drawing, forming part thereof.

The figure is a perspective view of a table show-

ing my design, the dominant feature thereof being the top, shown in full lines. The legs are shown in dotted lines, attached to the top, to indicate how the table top is incorporated into a complete table.

I claim:

The ornamental design for a table substantially as shown and described.

NATHAN P. BLOOM.
